TION OF PENNSYLVANIA.

WELT-KNITTING MACHINE.

1,140,783.

Specification of Letters Patent. Patented May 25, 1915.

Application filed September 28, 1911. Serial No. 651,813.

To all whom it may concern:

Be it known that we, FRANK B. WILDMAN and GEORGE L. BALLARD, a citizen of the United States, and a subject of the King of Great Britain, respectively, and residents of Norristown, Pennsylvania, have invented certain new and useful Improvements in Welt-Knitting Machines, of which the following is a specification.

10 Our invention relates to that type of latch needle rib knitting machine designed to produce tubular welts, and in which a single main thread is used, and an additional thread is thrown in when the welt is to be formed.

15 In carrying out our invention, we throw the additional thread into the cylinder needles instead of into the dial needles, thus overcoming certain mechanical difficulties 20 and causing the additional thread to appear on the face or outside of the fabric, this thread being at the choice of the operator of a different color or of different material from the body of the fabric.

25 Some of the mechanical features and connections disclosed herein are like those shown in an application for Letters Patent of the United States #623,261, April 25, 1911, patented Dec. 17, 1912, No. 1,047,355, 30 and in certain Letters Patent hereinafter mentioned.

35 In the accompanying drawings, Figure 1 is a plan view of a knitting machine of the Wildman type embodying our invention; Fig. 2 is a side view of a knitting head with the feed mechanism for the additional thread used in the formation of the two-walled welt; Fig. 3 is a view of the cam cylinder of the cylinder needles developed and 40 looking at the inside of the same; Fig. 4 is a front view of the feeding, cutting and clamping mechanism for the additional thread; Fig. 5 is a view of the cutting and clamping mechanism for the thread looking 45 from the left of Fig. 4; Fig. 6 is a bottom plan view of the cutting and clamping devices; Fig. 7 is a detail view of one of the cylinder cam posts.

50 The main thread is fed to the needles by a guide 1 of usual construction, and the additional thread to form the outer wall of the tubular welt is fed through a guide 2 diametrically opposite the main guide and consisting of an arm pivoted at 3 to a

55 bracket 4, said arm being operated to and from the needles to present the thread there- 60 to or remove it therefrom by means similar in some respects to that disclosed in Letters 65 Patent of the United States granted to J. B. Hipwell, #815,167, March 13, 1906, and 70 consisting generally of a star wheel 5 which, when operated by contact with a device on the frame, operates through gearing 6 and a cam shaft 7 to raise the lever or thread 75 guide arm or to allow it to fall under the action of the spring 8. At 9 is shown a cutting device for the additional thread, which is operated to sever it when the guide arm is raised, and at 10 is a clamp for holding the severed end of the thread so that when 80 the guide arm is again lowered the thread will be presented to the needles, the clamp insuring proper control of the thread until the needles have taken it. The mechanism for operating the cutter and clamp will be 85 referred to briefly hereinafter.

The star wheel 5 of the additional thread 90 feeder is operated by contact with a pin 11 carried by a plate 12 which is adjusted vertically into and out of line with the star 95 wheel by suitable pattern mechanism, (not shown).

One movement of the star wheel will throw the guide arm 2 up and the next action of the star wheel will permit the guide 85 arm to fall to present the thread to the cylinder needles.

The cams of the dial comprise a stitch cam 12' and an advancing cam 13, and this latter may be of the form known as a wing 90 cam, or a cam may be used such as is disclosed in Letters Patent of the United States granted to F. B. Wildman, #800,192, Sep- 95 tember 26, 1906, and carried by a two-part dial cap. Such a pivoted cam is illustrated at 13 pivoted at 14, and adjusted by a pin and slot connection at 15, when the lower cam carrying section 16 of the dial cap is move circumferentially.

For throwing the cam carrying section, 100 we employ mechanism similar to that dis- 105 closed in said patent consisting of a link 17 and arm 18 on a vertical shaft mounted in the cam cylinder and in turn operated by an arm 19 fixed to said shaft and by a second arm 20 on a shaft 21 geared to the shaft first mentioned, as is well known in this type of machine, these arms being at different ele-

vations and striking a pattern disk 22, the stem of which is mounted to move vertically in the fixed ring of the machine under the control of pattern mechanism which moves the disk to the plane of rotation of first one of the arms and then the other for the adjustment of the advancing cam. There is but a single set of cams in the dial.

The cams for the cylinder needles, shown in Fig. 3, comprise an advancing cam *a* and a stitch cam *b* for the main feed, and a cam *c* and cam *d* serving as clearing course cams, when the cylinder needles are to be cleared of their stitches, and as advancing and stitch cams for the additional feed when this is thrown in. The means for operating these cams will be described later.

The figure (3) shows the relation of the main and additional feeds and the clamp and cutter for the latter, to the said cams, and Fig. 1 shows the relation of the feeds to the single set of cams in the dial. The cam box or cylinder moves in the direction of the arrow *X* in Figs. 1 and 3, and therefore the needles in effect move along the cam path in the direction of the arrow *y*.

With the cams in the position shown, and with the dial cams in normal position of Fig. 1, plain rib fabric will be produced, the thread being taken from the single main thread guide 1 while the additional thread for the outside welt of the tubular welt is held out of action by its guide 2, and with its end clamped at 10. Having completed the rib fabric and having, if desired, thrown in a loose course by depressing the stitch cam *b* of the cylinder, the first action that takes place is the throwing inwardly or retracting of the pivoted cam 13 of the dial to allow the dial needles to simply hold their loops while the cylinder needles knit, say, two courses of welt fabric to prevent the work from raveling back when the clearing course is thrown in. After this the wing cam, if such be used, or the pivoted cam 13 is thrown outwardly to normal position for advancing the dial needles for taking the yarn again. During these actions the cam *c* is inactive.

After the cylinder welt courses have been knitted and the dial cam is restored to normal position as just mentioned, the cam *c* is raised from its inactive position shown in full lines, Fig. 3, to that shown in dotted lines. The cylinder needles are now advanced by this cam so that their loops get back of their latches, and as no thread is fed at this point (the thread guide 2 for the additional thread being held up), the cylinder needles, when retracted by the cam *d*, will shed their loops to form the clearing course. The cam *d* in the position shown in full lines is low enough to shed the loops for this clearing or dividing course.

The cylinder needles are now empty on

this revolution of the cams until they are operated by the cam *a*, when they advance and take thread from the main carrier at 1, the dial needles also take the thread from the carrier 1 at this time. Not having any old loops, however, no stitches are produced by the cylinder needles when they are lowered by the stitch cam *b*, but they simply hold this main thread to form the dividing course, said main thread also serving as a foundation for the welt when the additional thread is thrown in. The cylinder needles having received this foundation thread, they are next acted on by the cam *c* at the next revolution of the machine, and the cam *d*, 70 75 the guide 2 of the additional thread, however, having first been thrown down to present the additional thread to the cylinder needles which advance to take it by the action of the cam *c* which has already been advanced, as described. The needles then are immediately lowered by the cam *d*, thus forming stitches at this point in the circuit of the machine, where there are no corresponding stitch and retracting cams in the 80 dial so that plain fabric to form the outer wall of the welt will be formed here on the cylinder needles. 85

Before the cylinder needles again arrive at, or rather before being acted on again by the cam *a* in this revolution of the machine, and after the action above described has taken place of taking thread from the additional feeder to form the outer wall of the welt, the said cam *a* is lowered and the cylinder needles are prevented from taking thread from the main thread guide and therefore at this feed only the dial needles will take the thread, thus producing the inner wall of the tubular welt on this side of 100 105 the machine, while the outer wall of said welt will be produced at the opposite side of the machine at the additional thread guide and upon the cylinder needles.

It will be seen from the above that the 110 cams *c* and *d* serve a two-fold purpose, in that they advance and retract the needles of the cylinder to clear them and make them ready to receive the foundation thread for forming the outer welt wall, and they also 115 serve as advancing and retracting cams for the formation of the stitches on the cylinder needle in said wall. With the cam *d* in the position shown in full lines, the cylinder needles are retracted far enough to cast 120 off their stitches for the clearing course. When, however, the additional thread is thrown in, the cam *d* is simultaneously lowered to draw sufficient yarn to make stitches. This lowering of the cam *d* at the time the 125 additional thread is thrown into the cylinder needles is effected by a cam 7* on the shaft of the additional thread feeder acting on a lever 23 connected with a rock shaft 24 mounted on the frame or bracket of the ad- 130

ditional thread feeder, said shaft having an arm 24' overlying the stem of the cam *d* so that it will press the same down at the time the additional thread is thrown in to draw enough yarn to form a stitch. This cam post, as also the posts of the cams *c*, *a*, *b*, are spring pressed, the springs of *c* and *a* pressing the cams down, while the springs of cams *d* and *b* press them upward. 5 When the tubular welt is to be terminated and rib knitting resumed, the first action that takes place is the dropping of the cam *c* out of action and at the point where the last cylinder needle that has cleared its latch passes the additional thread guide 2, said thread is withdrawn by the raising of the guide and the thread is cut and clamped. 10 The advancing cam *a* being now raised from its inactive position, the cylinder needles take the thread from the main thread guide 1, and rib knitting starts from this point.

Any desired number of courses can be knit when the machine is making the outer and inner walls of the welt, these being 15 formed independently, the outer wall on the cylinder needles and the inner wall on the dial needles.

It will be observed that after the cam *c* is raised for clearing, it remains up to serve 20 as an advancing cam for the cylinder needles during the formation of the outer wall of the welt thereon. The cam *c* is operated by a cam disk 24^a acting on an arm or pin 25 extending from the post *c*^a of the cam *c*, the said cam disk being fixed to a hollow shaft 26, which is operated to lift the pin 25 and post *c*^a by an arm 27 striking and being moved by the pattern disk, said arm being 30 on a shaft geared to the hollow shaft 26, 40 and the cam being turned the other way to remove its incline or cam surface from beneath the pin by an arm 28 fixed to the hollow shaft striking the pattern disk 22. The stitch cam *b* is operated for the slack or 45 loose course by an arm 29 fixed to the shaft 30 which passes down through the hollow shaft 26, and has on its lower end a projection 31 entering a notch 32 in a ring 33 which encircles the knitting head and on the 50 other side of the machine is operated from the arms 34, 35 on a shaft 36, and the return arm 37 on a shaft 38 geared to the shaft 36, the shaft 38 having a projection 40 entering a recess in the ring, the arms 34, 35 and 37 55 being arranged to be struck and operated by the pattern disk 22 when the same is lifted into the plane thereof by the pattern mechanism. The arm 29 has studs to bear on inclines on a plate 41 secured to the post 60 *b*^a of the cam *b*, to press the said cam down wardly to different positions for the loose and slack course.

The cam *c* is operated in a manner similar to that described in the application of Wild- 65 man et al. Dated above described to give the

cam a step by step downward movement. The post *c*^a of said cam has a pin 42 bearing on the incline 43 of a cam disk 44 on a shaft 45 which has an arm 46 to be operated by contact with the pattern disk 22, and when 70 so struck the cam or incline is removed from under the pin and the cam post moves down under the action of its spring and until it is caught by a catch lever 47 which engages a notch 52, Fig. 7, in the side of the post. 75 This effects the first step in the downward movement of the cam, and the second step is effected by the arm 48 of the catch lever striking the disk 22 and moving it into the position shown, *i.e.*, to release the post *c*^a and allow the spring thereof to force it all the way down. This catch lever is pressed by a spring 49. The shaft of the cam disk 44 is geared to a shaft 50 of an arm 51 in a lower plane than the arm 46 and this, when 80 it strikes the disk 22 (the latter having been adjusted to the proper height), will turn the cam disk 44 and raise the cam post *c*^a and the cam *a*. The post has a notch as at 52, Fig. 7, with a beveled wall. The catch 85 47 engages this to hold the cam *a* in its intermediate position. When the post is raised from its low position the catch will move into the notch, but because of the incline the post can move on up to its high position. 90

Reverting to the thread cutting and clamping means: the cutter comprises the fixed blade 9 and a movable blade 9' pivoted at 9^a to a bracket 9^b. The movable blade is 100 pressed open by a spring 9^c, and it is closed to sever the yarn by a rod 9^d slidably mounted in the frame of the thread feeder, and acted on by the lever or arm *y*' pivoted to the frame of the feed attachment at 9^e, 105 its free end being in position to be operated by contact with the pin 11 which is raised and lowered by pattern mechanism. When the arm *y*' is swung inwardly by striking the pin, the shear blade 9' will operate in 110 conjunction with the fixed blade to sever the yarn, and the clamping blade 10 which moves with the blade 9' will engage and clamp the yarn upon the upper surface of the fixed blade over which the clamping 115 plate moves it, projecting, as shown in Fig. 6, slightly beyond the edge of the movable blade. This clamping plate is held by a pin 53 to the movable blade of the cutter to move therewith, but it is formed of a thin plate, and being held down on the shear blade by the spring 9^c, it will properly perform its clamping function. When the rod 9^d is moved inwardly 120 and the shear and clamp closed to cut and hold the thread, the said parts will be held in this position by the frictional engagement of a detent lever 54 pivoted to the frame and pressed by a spring 55, this spring being sufficient to overcome the 125 130

tendency of the spring 9^c to open the shear blade and clamp. When, however, the thread guide arm 2 is thrown down to introduce the additional thread to the cylinder needles, the detent lever 54 will be operated by one of the pins 56 on the end of the cam shaft which controls the guide arm 2, and the lever 23—24', and said detent lever will release the rod 9^d and the shears 10 and clamp will then be opened and the thread now taken by the cylinder needles. The additional thread 2^a passes under a guide finger 57, and thence to the guide arm 2, and by this the necessary amount of 15 slack is provided.

We have described various above features as examples of what may be employed in carrying out our invention. Some of these features we do not claim herein; some may be 20 altered and still come within the scope of our invention as defined by the scope of the appended claims.

It will be observed that by throwing the additional thread into the cylinder needles a 25 striping effect on the fabric may be secured because the outside wall of the welt may be knit in any desired color or material.

We claim as our invention:

1. A latch needle knitting machine having 30 a single main thread feed, the combination of the dial needles having their hooks directed radially outward, cylinder needles, means for feeding a single main thread, means for making a rib fabric from said 35 single thread comprising cams in the cylinder and dial, cams in the cylinder for knitting from an additional thread to make the outer wall of the welt, an additional thread feed, means for operating the same to feed 40 the thread to the cylinder needles, and means for adjusting the cams, first mentioned, of the cylinder to form the inner wall of the welt on the dial needles.

2. In a latch needle rib knitting machine, 45 dial needles, cylinder needles, a main thread feed, an additional thread feed, a single stitch cam and a single advancing cam for the dial needles, means for adjusting the advancing cam for weltting on the cylinder 50 needles, a stitch cam and an advancing cam for the cylinder needles, a second advancing and a second retracting cam for the cylinder needles, said second advancing cam being normally depressed during rib knitting 55 with the main thread, means for advancing said cam for clearing the cylinder needles, while the first advancing cam remains in operative position to cause the cleared cylinder needles to take the thread, means for then 60 lowering the first advancing cam for the formation of the welt on the dial needles with the main thread, means for operating the additional feed for presenting the additional thread to the cylinder needles at the 65 clearing course cam. said clearing course

cam causing the cylinder needles to take the thread from the additional feed for the formation of the outer wall of the welt on the cylinder needles, and means for giving the first and second advancing cylinder cams 70 their independent automatic adjustment, substantially as described.

3. In a latch needle rib knitting machine, dial needles, cylinder needles, a main thread feed, an additional thread feed, a stitch cam and an advancing cam for the dial needles, a stitch cam and an advancing cam for the cylinder needles, a second advancing and a second retracting cam for the cylinder needles, said second advancing cam being 80 normally depressed during rib knitting with the main thread, and said second retracting cam being normally above its stitch forming position, means for advancing said second advancing cam for clearing the cylinder needles in conjunction with said second retracting cam, means for lowering the first advancing cam for the formation of the welt on the dial needles with the main thread, means for operating the additional 85 feed for presenting the additional thread to the cylinder needles at the clearing course cam, said clearing course cam causing the cylinder needles to take the thread from the additional feed for the formation of the 90 outer wall of the welt on the cylinder needles, and means for depressing the second retracting cam from its clearing position to draw stitches from the additional thread on said cylinder needles.

4. In a latch needle rib knitting machine, dial needles, cylinder needles, a main thread feed, an additional thread feed normally inactive, an advancing cam and a stitch cam for the dial, an advancing cam and a stitch cam for the cylinder needles at the main feed, a second advancing cam and a second retracting cam for the cylinder needles at the additional thread feed, means for advancing the second advancing cam for clearing the cylinder needles, which are then advanced by the first advancing cam to take on a foundation thread for the outer wall of the welt at the main feed, means for presenting the additional thread to the cylinder needles, said cylinder needles being advanced and retracted at the second cams to form stitches from the additional thread for the outer wall of the welt, means for depressing the first advancing cam for the formation of the welt on the dial needles, and means for giving the first and second advancing cams of the cylinder their adjustments independently, substantially as described.

5. In a latch needle rib knitting machine, dial needles, cylinder needles, a main thread feed, and additional thread feed, a stitch cam and an advancing cam in each cam carrier, a second advancing and retracting cam in one cam carrier normally inactive, said second 125

100

105

110

115

120

125

130

set of cams serving both for clearing the needles operated thereby and for formation of stitches on said needles for one wall of the welt, means for throwing in the additional thread feed after the clearing action, 5 means for placing the first advancing cam out of action for the formation of the other wall of the welt on the other set of needles, and means for operating the first and second advancing cams independently, substantially as described.

6. In combination with a knitting machine, dial needles, cylinder needles, a main thread feed, needles and cams, including an 15 advancing cam and a retracting clearing course cam, an additional thread feed, means for operating the advancing cam to take the additional thread, means for operating the additional thread feed to prevent 20 the thread to or remove it from the needles, and means for simultaneously depressing the retracting cam for drawing stitches from said additional thread.

7. In combination in a knitting machine, 25 a dial, a cylinder, needles, a main thread feed, an additional thread feed, means for knitting rib fabric with the main thread or a plain fabric with said main thread on the dial needles, means for knitting a plain 30 fabric on the cylinder needles with the additional thread, means for presenting the additional thread to or removing it from the cylinder needles, and means for operating one of the cylinder cams for drawing 35 stitches from said additional thread when the said thread is presented to the needles, substantially as described.

8. In combination in a latch needle rib knitting machine, dial needles, cylinder needles, a main thread feed, an additional 40 thread feed normally inactive, an advancing cam and a stitch cam for the dial, an advancing cam and a stitch cam for the cylinder needles at the main feed, a second 45 advancing cam and a second retracting cam for the cylinder needles at the additional feed, said second retracting cam being normally in position to clear the needles and the second advancing cam being normally 50 retracted to prevent advancing the needles for clearing, means for advancing said second advancing cam to act in conjunction with the normally positioned second retracting cam for clearing the cylinder needles 55 which are then advanced by the first advancing cam at the main feed to take on a foundation thread for forming the welt, means for presenting the additional thread to the cylinder needles, at the second cylinder cams for the formation of the outer wall 60 of the welt, means for depressing the first advancing cam for the formation of the inner wall of the welt on the dial needles, and means for giving the first and second 65 advancing cams of the cylinder their ad-

justments independently, substantially as described.

9. In combination in a rib knitting machine with cylinder and dial needles, a single main thread feed for ribbing, an extra 70 thread feed for welting, means for welting on the dial and cylinder needles to make a double wall welt, means for throwing the extra thread feed in or out, and means for making a clearing course, said extra thread 75 being fed to the cylinder needles to show on the outside of the fabric without turning the same, substantially as described.

10. In combination with a knitting machine, an advancing and a retracting cam 80 for making a clearing course, an additional thread feed, mechanism for throwing the said feed into and out of working position, and a connection from said mechanism for adjusting the said retracting cam when the 85 additional thread is thrown into work, said cam, in its adjusted position, serving as a stitch cam for the additional thread, substantially as described.

11. In a latch needle rib knitting machine, dial needles, cylinder needles, a main thread feed, an additional thread feed, a stitch cam and an advancing cam for the dial needles, a stitch cam and an advancing cam for the cylinder needles, a second advancing and a second retracting cam for the cylinder needles, said second advancing cam being normally depressed during rib knitting with the main thread, means for advancing said cam for clearing the cylinder 90 needles, means for lowering the first advancing cam for the formation of the welt on the dial needles with the main thread, means for operating the additional feed for presenting the additional thread to the cylinder needles at the clearing course cam, said clearing course cam causing the cylinder needles to take the thread from the additional feed for the formation of the outer 95 wall of the welt on the cylinder needles, and a connection from the additional thread-operating means for depressing the second retracting cam simultaneously with the introduction of the additional thread to draw 100 stitches from the said additional thread on the cylinder needles, substantially as described.

12. In a latch needle rib knitting machine, a main thread feed, an additional thread feed, dial cams consisting of a stitch 105 cam and an advancing cam at the main feed, an advancing and stitch cam in the cylinder adjacent those of the dial for making rib fabric with the main thread, a second advancing cam and a second stitch cam in 110 the cylinder at the additional thread feed opposite the point in the dial where there is no advancing and stitch cam for the additional thread feed, and controlling means 115 for throwing the additional feed into op- 120 125 130

eration to make a welt on the cylinder and for throwing out of operation the first advancing cam of the cylinder for making a welt on the dial needles, substantially as described.

13. In a latch needle rib knitting machine, a main thread feed, an additional thread feed, dial cams consisting of a stitch cam and an advancing cam at the main feed, an advancing and stitch cam in the cylinder adjacent those of the dial for making rib fabric with the main thread, a second advancing cam and a second stitch cam in the cylinder at the additional thread feed operating the point in the dial where there is no advancing and stitch cam for the additional thread feed, and controlling means for throwing the additional feed into operation to make a welt on the cylinder and for throwing out of operation the first advancing cam of the cylinder for making a welt on the dial needles, said first advancing cylinder cam being moved step by step, substantially as described.

14. In a latch needle rib knitting machine, dial cams consisting of one advancing and one stitch cam, a main feed at which said cams are located, an additional feed at a point on the dial having no advancing and stitch cam, cylinder cams including an advancing and a stitch cam at the main feed, a second advancing and stitch cam at the additional feed, said second advancing and stitch cam serving both for clearing the cylinder needles and for the formation of stitches on said cylinder needles for one wall of the tubular welt, and means for placing the first advancing cam out of action for the formation of the other wall of the tubular welt on the dial needles, substantially as described.

In testimony whereof, we affix our signatures in presence of two witnesses.

FRANK B. WILDMAN.
